CN 103100747A, Dec. 29, 2015 First office action CN 103100747A.*Primary Examiner* — Patricia Palasik(74) *Attorney, Agent, or Firm* — Larry R. Meenan(57) **CLAIM**

The ornamental design for a double-sided, indexable cutting insert, as shown and described.

DESCRIPTIONFIG. 1 is an isometric front view from above of a double-sided, indexable cutting insert showing our new design; FIG. 2 is another isometric front view of the cutting insert; FIG. 3 is a right side view of the cutting insert, the left side view being identical to the right side view; FIG. 4 is a front view of the cutting insert, the rear view being identical to the front view; and, FIG. 5 is a top view of the cutting insert, the bottom view being identical to the top view.
The broken lines in the drawings depict unclaimed environmental subject matter.**1 Claim, 3 Drawing Sheets**| (56)	References Cited
